UNITED STATES PATENT OFFICE

WILLIAM C. GRAY, OF WASHINGTON, DISTRICT OF COLUMBIA, ASSIGNOR TO C. L. GOODWIN, OF RICHMOND, VIRGINIA

CEDAR LINING FOR CLOTHES CLOSETS

Application filed July 9, 1928. Serial No. 291,432.

This invention appertains to building construction and more particularly to clothes closets, or presses.

One of the primary objects of my invention is to provide a lining for clothes closets constructed from moth repellent material, such as red cedar which can be readily placed in a constructed closet without the use of nails or like fastening elements.

10 Another important object of my invention is to provide a cedar lining for closets which can be made in various sizes to fit various sizes of standard closets, the lining being so constructed as to permit the connection thereof with a closet by a layman.

15 A further salient object of my invention is to provide a cedar lining for clothes closets embodying panels cut to fit the walls and floor of the closet, the panels being hingedly connected together, whereby the lining can be sold as a single unit and whereby the lining can be folded into a compact space for shipping and readily manipulated to permit the introduction thereof into a closet.

20 A further object of the invention is the provision of novel means for associating molding with the lining during the placing of the lining in the clothes closet, the molding acting as means for reinforcing the lining and for holding the lining in proper position against collapsing.

25 A still further object of the invention is to provide a folding cedar lining for closets of the above character, which will be durable and efficient in use, one that will be simple and easy to manufacture, and one which can be placed upon the market at a reasonable cost.

30 With these and other objects in view, the invention consists in the novel construction, arrangement and formation of parts, as will be hereinafter more specifically described, claimed, and illustrated in the accompanying drawings, in which drawings:—

35 Figure 1 is a vertical transverse section through the closet having my novel cedar lining incorporated therewith.

40 Figure 2 is a section through the closet taken on the line 2—2 of Figure 1, showing my lining incorporated therewith.

45 Figure 3 is a horizontal section through the closet taken on the line 3—3 of Figure 1 looking in the direction of the arrows, showing my lining incorporated therewith.

50 Figure 4 is a vertical section taken on the line 4—4 of Figure 1 looking in the direction of the arrows, showing my improved lining incorporated therewith.

55 Figure 5 is a rear elevation of the lining in its spread out condition prior to being folded.

60 Figure 6 is a perspective view of my improved lining showing the same in its partly folded condition.

65 Figure 7 is a detail fragmentary perspective view illustrating one corner of the lining after the same has been placed in position showing the use of the quarter round reinforcing molding.

70 Figure 8 is a detailed vertical section taken on the line 8—8 of Figure 1 on an enlarged scale illustrating the point of connection of two of the panels with the reinforcing molding.

75 Referring to the drawing in detail, wherein similar reference characters designate corresponding parts throughout the several views, the letter A generally indicates my improved cedar lining and B a clothes closet or press with which the same can be associated.

80 The clothes closet or press B has simply been shown to illustrate the use of my improved lining A and is of common construction and is provided with the ordinary door opening 10 provided with the frame 11 which supports the swinging door 12.

85 My improved lining A is constructed from stock of a standard thickness and can be made in various sizes to fit closets or can be made in any size to fit particular closets and fit in its folded condition, as will be later described to the user.

90 The lining A comprises a rear wall panel 15, side wall panels 16, and 17, a top wall panel 18, and a bottom wall panel or floor panel 19. These panels 16, 17, 18 and 19 are all connected by the use of suitable hinges 20 to the side edges of the rear wall panel 15, and I 100

prefer to have these hinges countersunk as shown.

The side wall panels 16 and 17 support, what I term front jamb panels 21 and 22 and 5 these front jamb panels are connected to the front edges of the side panels 16 and 17 by hinges 22' which are also disposed on the rear of the lining and countersunk in position. The top wall 18 at its front edge supports, 10 which I term a front jamb panel 24 which is also connected by means of hinges 25 with said top panel 18.

By this arrangement the entire lining can be folded to occupy a minimum amount of 15 space during shipping and will also facilitate placing of the lining in position as after the lining is inserted in the closet, the various panels can be swung into place.

By referring to Figures 1 and 3 of the 20 drawings it can be seen that the rear panel 15 fits against the rear wall of the closet, while the side panels fit the side walls of the closet and the top panel 18 fits the top wall of the closet, while the lower panel engages the floor 25 of the closet. The jamb panels 21, 22, and 24 engage the front wall of the closet around the door opening 10 as clearly shown.

I employ a novel means for holding the 30 lining rigidly in position in the closet against movement and this means entirely obviates the necessity of using fastening elements, which not only necessitates the expenditure of time but is also detrimental to the walls of a finished closet. This means consists of 35 the use of quarter round molding pieces 26 which are cut to fit and which are placed at the juncture of all of the panels, as is clearly shown in the drawings. This molding extends from the top to the bottom of the closet 40 and from one side to the other and from the front to the back of the closet and the molding can be held in place by suitable brackets 27 which also function to further add rigidity to the lining.

45. From the foregoing description, it can be seen that I have provided a novel cedar lining which is ready to be immediately applied to the closet and which can be shipped in a collapsed condition from the manufacturer to 50 the user.

Changes in details may be made without departing from the spirit or the scope of the invention, but:—

What I claim as new is:

55. 1. The combination with a clothes closet, of a removable lining therefore comprising a plurality of panels for engaging the walls thereof, means hingedly connecting said panels together, reinforcing molding for engaging the panels at the point of juncture thereof for holding the lining in an assembled position in the closet, and means for connecting the molding to the adjacent panels.

60. 2. A removable and collapsible lining for 65 clothes closets comprising a main rear wall

hingedly connected to said main rear wall panel, jamb panels hingedly connected to the side and top panels, quarter round molding strips for engaging the panels at the point of juncture of said panels for holding the panels against movement when placed in set up condition, and means for connecting the molding strips to the panels.

3. A removable and collapsible lining for 75 clothes closets comprising a main rear wall panel, side, top and bottom wall panels hingedly connected to said main rear wall panel, jamb panels hingedly connected to the side and top panels, quarter round molding pieces 80 for engagement with the lining at the point of juncture of said panels to hold said panels against movement, and brackets connected with said panels and engaging said molding strips for preventing movement thereof.

4. A removable and collapsible lining for 85 clothes closets comprising a main rear wall panel formed of rigid material, side wall panels hingedly connected to the edges of the rear wall panels, top and bottom wall panels 90 hingedly connected to the top and bottom edges of the rear wall panel, top and side jamb panels hingedly connected to the top and side wall panels, and means engaging said panels at the juncture thereof for holding 95 the panels in set up condition.

In testimony whereof I affix my signature.

WILLIAM C. GRAY.
